LASTING MACHINE

William Thomas Buckingham Roberts, Leicester,
England, assignor to United Shoe Machinery
Corporation, Flemington, N. J., a corporation of
New Jersey

Application September 13, 1944, Serial No. 553,892
In Great Britain October 5, 1943

8 Claims.

(Cl. 12—14)

This invention relates to lasting machines, and is herein illustrated as applied to a power-operated toe-lasting machine constructed generally as disclosed in United States Letters Patent No. 2,134,148, granted on October 25, 1938, on an application of mine. It is to be understood, however, that the invention is not limited to machine organizations of that particular character.

The machine shown in the above-mentioned Letters Patent is provided with wipers movable to wipe the marginal portion of an upper about the toe end of a last inwardly over an insole on the last. Associated with the wipers are automatic power-operated mechanisms arranged respectively to advance them lengthwise of the shoe and to close them inwardly over the insole widthwise of the shoe, these mechanisms serving thereafter to retract the wipers from the shoe to predetermined positions. When so retracted their edges are commonly close to the upper of the toe end of a shoe correctly positioned in the machine and assist in properly positioning the shoe laterally.

When a shoe is presented to the machine the toe-end portion of the upper is commonly in a condition resulting from an earlier pulling-over operation and has ears which project outwardly from the last at the corners of the toe. While these ears, if the upper is of comparatively thin or soft material, may be readily pressed toward the last by the edges of the wipers, it has been found that in a comparatively thick or heavy upper they may interfere with the presentation of the shoe to the machine in proper position for the lasting operation. The present invention accordingly provides novel means whereby the retracted positions of the wipers may be changed, so as to provide more clearance between their edges and the last in operating on thick or heavy uppers than in operating on light uppers. In the construction shown the above-mentioned mechanisms for advancing and for closing the wipers respectively, which are operated by cams, have associated with them stop mechanism which may be used to limit the retractive movements of the wipers to shorter movements than would otherwise be effected; and to permit such limitation of the retractive movements of the wipers the cams have portions which are yieldable when the stop mechanism is in use. When the machine is to operate on comparatively light uppers, therefore, the stop mechanism is moved to operative position, and when comparatively heavy uppers are to be lasted

it is moved to inoperative position so that there will be more clearance between the edges of the wipers and the last. It will be evident that such variation of the limits of the retractive movements of the wipers does not affect the limits of their wiping movements.

The novel features of the invention, including various novel details of construction and combinations of parts, will now be more particularly described with reference to the accompanying drawing and thereafter pointed out in the claims.

In the drawing,

Fig. 1 is a view in right-hand side elevation of a portion of the wiper-operating means of the machine shown in the previously mentioned Letters Patent, together with means provided by this invention for varying the retracted positions of the wipers;

Fig. 2 is a right-hand side elevation of a portion of the wiper-operating means not clearly visible in Fig. 1; and

Fig. 3 is a plan view showing the toe wipers and a shoe in position to be operated upon, the wipers being in their retracted positions.

While the machine to which the invention is herein shown as applied may be assumed to be constructed generally as disclosed in the above-mentioned Letters Patent, it may be modified in some respects as disclosed in other United States Letters Patent granted on applications of mine, including Letters Patent No. 2,135,677, granted on November 8, 1938, which discloses a preferred construction of means for supporting the shoe and for determining its position lengthwise in the machine. With the shoe thus positioned, it is operated upon by wipers 2 (Fig. 3) which are advanced bodily lengthwise of the shoe and are closed inwardly widthwise of the shoe to wipe the marginal portion of the toe end of the upper inwardly over the insole. For thus closing the wipers there is provided wiper-closing mechanism constructed substantially as disclosed in Letters Patent No. 2,134,148, this mechanism including a cam-operated lever 4 which corresponds to the lever 119 shown in said Letters Patent and is mounted for swinging movements about a rod 6. This lever is operated by a cam 8 fast on a cam shaft 10, the cam having in one side thereof a cam track 12 in which lies a roll 14 mounted on the upper end of the lever 4. For advancing the wipers lengthwise of the shoe there is further provided wiper-advancing mechanism also constructed substantially as disclosed in the last-mentioned Letters Patent, this mechanism including a lever 16

corresponding to the lever 135 of said Letters Patent and mounted to swing about the rod 6. The lever 16 is operated by a cam 18 on the cam shaft 10, this cam being provided in one side thereof with a cam track 20 in which lies a roll 22 mounted on the upper end of the lever 16. It will be understood that the inner walls of the cam tracks 12 and 20 impart to the wipers their wiping movements over the shoe and that the outer walls of the cam tracks impart to them their retractive movements.

For purposes of this invention there are provided two stop members 24 which may be moved into positions to engage respectively the front faces of the levers 4 and 16 in locations below the rod 6, as shown in Fig. 1, to limit these levers to shorter wiper-retracting movements than they would otherwise receive. These members are adjustably mounted in a lever 26 which is mounted to swing about a horizontal shaft 28 extending laterally of the machine. Pivotally connected to the lever 26 is a link 30 which extends forwardly to the front of the machine into position within convenient reach of the operator. By use of this link the operator may swing the lever 26 upwardly to withdraw the stop members 24 from their operative positions to idle positions. To maintain the stop members in their idle positions, where they do not affect the movements of the levers 4 and 16, there is formed on the front end of the link 30 a hook 32 arranged to hook over a rod 34 extending laterally of the machine.

To permit the shorter wiper-retracting movement of the wiper-closing lever 4 when the corresponding stop member 24 is in position to control this lever, that portion of the cam track 12 in which the roll 14 lies when the wipers are in their retracted positions is widened, and the cam 18 has pivotally mounted thereon at 36 a cam piece 38 controlled by a spring 40 on the cam. This cam piece has thereon a cam face 42 normally parallel to the opposite face of the cam track 12. When the stop members 24 are in their idle positions the cam piece 38, projected by the spring 40 into the widened portion of the cam track, acts on the lever 4 to open the wipers to positions determined by the inner wall of the cam track. When the stop members are in their operative positions the cam piece is forced outwardly in the widened portion of the cam track by engagement of the roll 14 therewith after the wiper-retracting movement of the lever 4 has been stopped by the corresponding stop member. Similarly, that portion of the cam track 20 in which the roll 22 on the wiper-advancing lever 16 lies when the wipers are in their retracted positions is widened, and the cam 18 has in it a plunger 44 controlled by a spring 46 on the cam. When the stop members 24 are in their idle positions the plunger 44 acts on the lever 16 to retract the wipers lengthwise of the shoe to positions determined by the inner wall of the cam track 20, and when they are in their operative positions the plunger is forced outwardly by the roll 22 after the wiper-retracting movement of the lever 16 has been stopped by the corresponding stop member.

It will be understood that when uppers made of comparatively thick or heavy material are to be operated upon the stop members 24 will be withdrawn from their operative positions, so that the wipers will receive their full retractive movements as illustrated in Fig. 3. This will provide sufficient clearance for the projecting ears *a* of

the upper at the corners of the toe to permit the shoe to be presented without difficulty in proper position for the lasting operation. When uppers of comparatively thin or light material are to be operated upon, the operator swings the stop members to their operative positions by means of the link 30. In order to avoid the necessity of forcing the lower arms of the levers 4 and 16 rearwardly against the resistance of the springs 40 and 46, he may cause the machine to operate without any shoe therein and may move the stop members to their operative positions when the lower arms of the levers are moved rearwardly in the course of the cycle of operations. To vary the retracted positions of the wipers when the stop members are in use, these members are adjustable relatively to the lever 26. It will be understood that regardless of the starting positions of the wipers the limits of their wiping movements over the shoe, effected by the inner walls of the cam tracks 12 and 20, are the same.

Having described the invention, what I claim as new and desire to secure by Letters Patent of the United States is:

1. In a lasting machine, wipers movable to wipe the marginal portion of an upper about the toe end of a last inwardly over an insole on the last, automatic power-operated means for thus operating the wipers and for thereafter retracting them from the shoe, and means for changing the limits of the retractive movements of the wipers by control of said power-operated means while maintaining the limits of their wiping movements unchanged.
2. In a lasting machine, wipers movable to wipe the marginal portion of an upper about the toe end of a last inwardly over an insole on the last, automatic power-operated means for thus operating the wipers and for thereafter retracting them from the shoe, and stop mechanism for changing the limits of the retractive movements of the wipers by limiting the movement of a portion of said power-operated means while maintaining the limits of the wiping movements of the wipers unchanged.
3. In a lasting machine, wipers movable to wipe the marginal portion of an upper about the toe end of a last inwardly over an insole on the last, automatic power-operated means for thus operating the wipers and for thereafter retracting them from the shoe, and stop mechanism for shortening at the will of the operator the retractive movements of the wipers, a portion of said power-operated means being yieldable to permit such control of the wipers by said stop mechanism.
4. In a lasting machine, wipers movable to wipe the marginal portion of an upper about the toe end of a last inwardly over an insole on the last, automatic power-operated means for thus operating the wipers and for thereafter retracting them from the shoe, and stop mechanism movable either into or out of position to engage a portion of said power-operated means and thereby to limit the retractive movements of the wipers to shorter movements than otherwise effected by said means, another portion of said power-operated means being yieldable to permit such limitation of the retractive movements of the wipers.
5. In a lasting machine, wipers movable to wipe the marginal portion of an upper about the toe end of a last inwardly over an insole on the last, automatic power-operated mechanisms arranged

respectively to advance said wipers lengthwise of the shoe and to close them inward laterally of the shoe, said mechanisms being movable thereafter to retract the wipers from the shoe, and means for changing the limits of the retractive movements of the wipers by control of said mechanisms while maintaining the limits of their advancing and closing movements unchanged.

6. In a lasting machine, wipers movable to wipe the marginal portion of an upper about the toe end of a last inwardly over an insole on the last, mechanisms arranged respectively to impart to said wipers advancing movements lengthwise of the shoe and closing movements laterally of the shoe, cams for operating said mechanisms to impart the advancing and closing movements to the wipers and thereafter to retract them from the shoe, and means for shortening the wiper-retracting movements of said mechanisms independently of said cams, said cams having portions yieldable to permit such shortening of the movements of the mechanisms.

7. In a lasting machine, wipers movable to wipe the marginal portion of an upper about the toe end of a last inwardly over an insole on the last, mechanisms arranged respectively to impart to said wipers advancing movements lengthwise of

the shoe and closing movements laterally of the shoe, cams for operating said mechanisms to impart the advancing and closing movements to the wipers and thereafter to retract them from the shoe, and stops arranged to engage said mechanisms to shorten the retractive movements of the wipers, said cams having portions yieldable to permit the mechanisms thus to be controlled by said stops.

8. In a lasting machine, wipers movable to wipe the marginal portion of an upper about the toe end of a last inwardly over an insole on the last, mechanisms including levers arranged respectively to impart to said wipers advancing movements lengthwise of the shoe and closing movements laterally of the shoe, cams having therein cam tracks for operating said levers to impart the advancing and closing movements to the wipers and thereafter to retract them from the shoe, and stops movable at the will of the operator into positions to shorten the wiper-retracting movements of said levers, said cams having portions yieldable to permit such shortening of the movements of the levers.
